UNITED STATES PATENT OFFICE.

JOHN BRANDWOOD, THOMAS BRANDWOOD, AND EDWARD BRANDWOOD, OF BURY,
ENGLAND.

GASEOUS OR LIKE TREATMENT OF TEXTILE MATERIALS.

1,095,796.

Specification of Letters Patent.

Patented May 5, 1914.

Application filed February 12, 1913. Serial No. 747,964.

To all whom it may concern:

Be it known that we, JOHN BRANDWOOD, THOMAS BRANDWOOD, and EDWARD BRANDWOOD, all subjects of the King of Great Britain and Ireland, and all residents of Bury, in the county of Lancaster, England, have invented certain new and useful Improvements in the Gaseous or like Treatment of Textile Materials, of which the following is a specification.

This invention relates to improvements in that process of fixing dyes or the like which are wound upon perforated cores by forcing air externally and radially through such 15 yarns. The perforated cores carrying the dyed yarns are contained in a vessel to which air is admitted under pressure, the air passing through the wound yarns and the perforated cores. In carrying such a process into effect in the ordinary manner the 20 amount of air supplied is of such small quantity and is under such low pressure, as for example, when supplied from a blower, that it cannot pass into and penetrate the 25 substance of the yarns especially when they are tightly wound, but escapes through the spaces or interstices between windings or layers of windings. The component yarns, therefore, are only superficially treated, and 30 as the interstices in some parts of a cop or the like will provide easier passage for air than those in some other parts, an unequal fixing effect is obtained even upon surfaces of the yarns. This and the fact that 35 the interiors of the yarns are not treated equally with their surfaces results in stripes and spots in the fabrics produced from the 40 yarns.

According to this invention the air is supplied in such large volume and at such 45 high pressures that it cannot all pass through the interstices between yarns, and a large quantity of it is actually caused to pass through the interiors of even the most tightly wound yarns. With this treatment there is thorough oxidation of the dye contained in the innermost parts of the substance of all yarns, and a regular color effect is thus obtained.

50 In carrying this invention into effect any convenient pressure above atmospheric may be used and for some uses pressures up to a hundred pounds per square inch may be employed.

The accompanying drawings illustrate 55 appliances by means of which our invention may be carried into effect.

Figure 1 is a sectional elevation of an apparatus by means of which cops mounted on perforated skewers or spindles of the type 60 common in cop dyeing and like processes may be air permeated. Fig. 2 is a like view of another apparatus for use in the air permeation of warps wound upon a beam. Fig. 3 is a like view of apparatus forming part 65 of our invention for air permeating cops which are not mounted on perforated skewers or spindles. Fig. 4 is a sectional view of part of Fig. 3.

Equivalent parts are marked by like letters of reference where they occur in the different figures.

Referring first to Fig. 1 A is a cylindrical steel vessel capable of resisting high pressures and is closed for use by the lid B. C 75 is a circular plate carrying a number of perforated and hollow skewers D which bear the cops E. The interiors of the skewers open to the under part of the plate C. The plate C is put into place within or is 80 removed from the vessel A through the upper end when the lid is removed. When the plate C is in place in the vessel its edge rests upon and makes an air tight joint with an internal flange or web F inwardly projecting from the wall of the vessel A. When the plate is thus properly in place and the lid of the vessel is secured in its closed position, air under the before stated conditions 85 of volume and pressure is admitted through 90 the pipe G to the upper part of the vessel. To reach the exhaust pipe H leading to the atmosphere, air must pass through the substance of the fibers in the cops. The air pressure in the upper part of the vessel may 95 alone be relied upon to press the plate C down upon its seat on the flange F, but if desired screw or other pressure devices may be used to maintain a tight joint.

Fig. 2 illustrates how a perforated hollow 100 beam wound with warps may be similarly treated. The beam D is placed with its lower end upon an air tight seat in the lower part of the vessel A surrounding the pipe H leading to the atmosphere. As before air 105 under the requisite conditions of volume and pressure is led into the upper part of the closed chamber. The upper end of the beam

is closed. To escape to the atmosphere air must pass through the substance of the material E wound upon the beam. For use in this apparatus the beam may be replaced by 5 a perforated hollow cylinder bearing cops, cheeses or the like disposed upon it.

In Figs. 3 and 4 the cops E which are to be air permeated are placed in suitably shaped seats between grid plates C, the 10 openings J in the grid being plugged by cops. Several of such grid plates may be placed one above another upon a perforated plate or partition C¹ in the lower part of the vessel A so that several tiers of cops can 15 be simultaneously permeated. The perforations J¹ in the plate C¹ come directly below the perforations J in the plates C. Air under the required conditions of volume and pressure passes downward through and 20 from a cop to and through others which are below it, and to the exhaust pipe. Textile materials in other forms than cops may be laid upon grids or other perforated supports for like treatment with air as described.

25 The treatment with air (including in this

expression any suitable or appropriate gases or vapors) according to this invention may be for any of the purposes for which air is used according to the present methods. For example it may be to remove liquors of a 30 treatment from the material, or to develop a dye and fix it upon the fibers as already hereinbefore indicated.

What we claim is:—

The method of fixing dyes in textile material wound upon a perforated core by forcing air through such material radially inward under such pressure and in such quantity that air is compelled to pass through the interior of the yarn, substantially as set forth.

In witness whereof we have hereunto set our hands in the presence of two subscribing witnesses.

JOHN BRANDWOOD.

THOMAS BRANDWOOD.

EDWARD BRANDWOOD.
